2 SHEETS—SHEET 2.

UNITED STATES PATENT OFFICE.

CHARLES LIBERMAN, OF NEW YORK, N. Y.

LOCK.

1,177,640.

Specification of Letters Patent.

Patented Apr. 4, 1916.

Application filed August 19, 1915. Serial No. 46,314.

To all whom it may concern:

Be it known that I, CHARLES LIBERMAN, a citizen of the United States, residing at New York, in the county of New York and State of New York, have invented certain new and useful Improvements in Locks; and I do hereby declare the following to be a full, clear, and exact description of the invention, such as will enable others skilled in the art to which it appertains to make and use the same.

This invention relates to new and useful improvements in locks and the principal object of the invention is to provide a novel means for operating the number of bolts of a lock simultaneously.

Another object of the invention is to provide a lock and a casing for the lock, which may be readily attached to a door with little effort on the part of the person applying the same.

A still further object of the invention is to provide an efficient and simple lock capable of being readily operated and also being of such a construction as to be easily and cheaply manufactured.

With these and other objects in view, the invention consists in the novel combination and arrangement of parts which will be fully set forth in the following specification and accompanying drawings, in which:

Figure 1 is a view illustrating my improved lock in place in a door. Fig. 2 is a vertical sectional view through the lock. Fig. 3 is a vertical sectional view through the lock taken at right angles to the point of Fig. 2. Fig. 4 is a sectional view on line 4—4 of Fig. 2. Fig. 5 is a sectional view on line 5—5 of Fig. 2. Fig. 6 is a view similar to Fig. 2, showing portions of the lock removed to more clearly illustrate the details of construction, and Fig. 7 is a view similar to Fig. 6, showing still further portions of the lock removed.

Referring now to the drawings by characters of reference, the numeral 1 designates the face plate, which forms the base of the lock. This face plate is formed intermediate its ends with the flanges 2, which operate with the flanges 3 in supporting the side walls 4 of the lock in place. These side walls are connected at their extreme terminals by the end wall 5 and it will thus be seen that a chamber is provided in which the operating means are confined. Secured near each end of the base plate 1 are the

casings 6, in which the coöperating bolts are slidable.

Slidable in the casing formed by the side walls 4 and the end wall 5 is the central bolt 7 which is supported on the U-shaped frame 8, the arms of which are formed with the recesses 9, in which the springs 10 rest. These springs are of the compressed coil type and are designed to engage the end walls of each recess and the wall of the plate 1. The face 11 of the U-shaped frame 8 is designed to be engaged by the key of the lock when the same is operated to throw the bolt into locking position.

Overlying the U-shaped frame 8 is a suitable U-shaped guard plate 12, the bight portion 13 of which is disposed at the opposite side of the casing hereinbefore referred to.

Slidable laterally within the casing and positioned on top of the plate 13 are the plates 14 to the ends of which are secured the laterally extending rods 15, the upper ends of which extend into the casing 6 previously referred to. Pivoted to each rod 16 is a link 17, the opposite end of which is pivoted to the locking bolt 18 in each of the casings 6 so that when the rod moves upwardly, the bolt will be thrown to its unlocked position. In order to normally tend to hold the bolt in locked position there is provided a suitable spring 19 which surrounds each bolt and abuts a pin 20, extending through the bolt and the rear end of each casing 6.

The key used in connection with the lock is best illustrated in Figs. 2 and 5 and comprises the shank or stem 21, provided with the head or bit 22. This head or bit is so constructed that when in the locked position illustrated in Fig. 2, the bolt 7 will be forced outwardly and the members 14 will be moved inwardly, thus allowing the bolts 18 to move outwardly. Upon turning the key to unlock the device, it will be seen that it will assume the position illustrated by the dotted lines in Fig. 2 and the springs 10 within the recesses 9 in the frame 8 will force the bolts inwardly and the bolts 18 will be moved inwardly for the reason that the bit 21 of the key engages the edge of each of the members 14 thereby forcing the same upwardly and exerting pressure on the bar 15, which will move the same upwardly and cause the link to force the bolts 18 as indicated in the dotted line position.

From the foregoing it will be apparent

that a particularly simple and efficient lock is provided which is capable of being readily actuated and can be accommodated in a comparatively small amount of space. It will 5 also be evident that a lock constructed in this manner may be easily and quickly applied to a door as there is very little cutting to do in order to mortise the same.

While in the foregoing there has been 10 shown and described the preferred embodiment of this invention, it is to be understood that such changes may be made in the combination and arrangement of parts as will fall within the spirit and scope of the appended claims.

What is claimed is:—

1. A lock comprising end casings, a central casing, end bolts slidably mounted in said end casings, springs in said end casings 20 to normally hold said end bolts projected, a central bolt slidably mounted in said central casing, a spring mounted in said central casing to normally hold said central bolt retracted, and means adapted to be operated 25 by the turning of a key in one direction to retract said end bolts and to permit said central bolt to be retracted by its spring, said means being adapted to be operated by the turning of the key in the reverse direction to project said central bolt and to permit said end bolts to be projected by their 30 springs.

2. A lock comprising end casings, a central casing, bolts slidably mounted in said 35 end casings, springs in said end casings to normally hold said bolts projected, a frame slidably mounted in said central casing, a central bolt carried by said frame, a spring in said central casing to normally hold said

central bolt retracted, said frame being 40 adapted to be operated by the turning of a key in one direction to project said central bolt, the turning of the key in the reverse direction permitting said central bolt to be retracted by its spring, and means adapted 45 to be operated by the turning of the key in said reverse direction to retract said end bolts, said means permitting said end bolts to be projected by their springs when the key is turned in said first named direction. 50

3. A lock comprising end casings, a central casing, bolts slidably mounted in said end casings, springs in said end casings to normally hold said end bolts projected, a frame slidably mounted in said central casing, a central bolt connected to said frame, a spring in said central casing to normally hold 55 said central bolt retracted, said frame being adapted to be operated by the turning of a key in one direction to project said central bolt, the turning of the key in the reverse direction permitting the central bolt to be retracted by its spring, plates slidably mounted in said central casing and adapted to be operated by the turning of the key in 60 said reverse direction, and a connection between each plate and each end bolt, said connection retracting said end bolts when the key is turned in the reverse direction and permitting said end bolts to be projected by their springs when the key is turned in the first named direction. 65

In testimony whereof I affix my signature in presence of two witnesses.

CHARLES LIBERMAN.
